UNITED STATES PATENT OFFICE.

FRED A. GUILLETTE, OF TAUNTON, MASSACHUSETTS.

SELF-THREADING LOOM-SHUTTLE.

1,154,011.

Specification of Letters Patent. Patented Sept. 21, 1915.

Application filed May 14, 1913. Serial No. 767,731.

To all whom it may concern:

Be it known that I, FRED A. GUILLETTE, a citizen of the United States, residing at Taunton, in the county of Bristol and State 5 of Massachusetts, have invented certain new and useful Improvements in Self-Threading Loom-Shuttles, of which the following is a specification.

This invention relates to loom shuttles of 10 the self-threading type, and has for its object an improvement in shuttles of this character which is intended to secure reliability and certainty in the self-threading operation.

15 In carrying out its general object of securing certainty of action in the self-threading operation of the shuttle, the present invention contemplates a novel construction and arrangement of parts which adapt the 20 shuttle for use either as a right hand or left hand shuttle, while at the same time providing means whereby the shuttle will readily and easily thread itself while in flight.

Another object of the invention is to provide 25 a self-threading device for loom shuttles which requires practically no alteration in the construction of the shuttle body and a minimum amount of cutting the same, which is an advantage over constructions 30 wherein it is sometimes necessary to cut and slit the delivery head of a shuttle body to such an extent as to materially weaken and otherwise damage the same.

Another and distinct object of the present 35 invention is to provide a self-threading device having what is termed a top delivery eye for the thread or filling, as distinguished from the side delivery eye which is almost universally used. By reason of the 40 provision of a top delivery eye for the thread or filling, the present invention possesses a marked advantage over the side delivery eye types of shuttles, not only in the particular of adapting the shuttle for "right" or "left" 45 use, but also because the improved construction prevents the cutting of the filling or thread which often happens in the side delivery shuttles since with the latter the filling thread strikes between the shuttle and 50 the swell or binder of the shuttle box and is frequently cut or broken thereby. Furthermore, in the side delivery eye shuttles many cuts of cloth are spoiled by reason of the thread being soiled by oil when it strikes

between the shuttle and the swell or binder 55 of the shuttle box.

A special object of the invention is to provide a self-threading guide for loom shuttles which positively causes the thread to automatically be threaded into the guide on 60 the first throw of the shuttle across the loom.

With these and many other objects in view which will readily appear as the description progresses, the invention consists in the novel construction, combination, and 65 arrangement of parts hereinafter more fully described, illustrated, and claimed.

The essential features of the invention involved in carrying out the objects above indicated are necessarily susceptible of embodiment in different forms of construction without departing from the spirit or scope of the invention, but for illustrative purposes, several preferred and practical forms of the invention are shown in the accompanying drawings in which—

Figure 1 is a perspective view of the delivery end portion of a loom shuttle having fitted thereto a preferable form of self-threading guide constructed in accordance 80 with the present invention. Fig. 2 is a central vertical longitudinal sectional view of the form of the invention shown in Fig. 1. Figs. 3 and 4 are details perspective and side views respectively of the preferred 85 form of self-threading guide shown in Figs. 1 and 2. Figs. 5 and 6 are top plan and longitudinal sectional views respectively of the delivery end portion of a loom shuttle fitted with a simplified form of self-threading guide embodying the present invention. Fig. 7 is a detail in perspective of the form 90 of guide illustrated in Figs. 5 and 6. Fig. 8 is a detail in perspective of another form of guide that may be employed. Fig. 9 is a cross sectional view of the form of guide 95 shown in Fig. 8, on the line 9—9. Fig. 10 is a detail in perspective of still another form of guide that may be utilized in carrying out the present invention. Fig. 11 is a 100 cross sectional view on the line 10—10 of Fig. 10.

Like reference characters designate corresponding parts in the several figures of the drawings.

The practical and fundamental features of the invention are well exemplified by the form of the device illustrated in Figs. 1, 2,

3, and 4 of the drawings, and referring first to these figures, it will be observed that the numeral 1 designates the shuttle body of the ordinary conventional construction. The 5 shuttle body is provided with the usual longitudinal recess 2 which accommodates the bobbin 3 for the filling thread and also with the usual delivery head 4, through which the filling thread is supplied to the loom as 10 the shuttle travels across the same.

According to the present invention it is proposed to deliver the filling thread, designated by the letter α in the drawings, from the top to the longitudinal center of the delivery head 4 of the shuttle body. That is to say, it is proposed to have the delivery eye for the filling thread located not only in and at the top of the shuttle head 4, but also centrally between the sides of said head 15 so as to lie in the plane of the vertical central longitudinal axis of the shuttle body. This feature is present in all forms of the invention, and the form of the device shown in Figs. 1 to 4 inclusive of the drawings, the 20 same is taken care of by properly positioning the device within the delivery end portion of the shuttle body. The said device as shown in these figures of the drawings primarily includes a guide sleeve or tube, 25 designated by the numeral 5, and preferably consisting of a metal tube of short length. This guide sleeve or tube 5 is open at both ends and is provided in one side thereof with a longitudinally disposed threading slot 6 which is maintained in open communication with a threading slit 7, of angular form piercing both legs of an angular bracket plate 8 and terminating at its ends 30 respectively in the receiving and delivery 35 eyes 9 and 10, as best seen in Fig. 3 of the drawings.

The angular bracket plate 8 may consist of a simple stamping that can be readily screwed or otherwise conveniently fastened 45 as at 11 within a correspondingly shaped seat or recess 12 formed within and on the shuttle head 4 at the delivery end of the bobbin recess 2. The said bracket or bracket plate 8 is accurately positioned in its seat 50 12 within the head 4 of the shuttle body so that the delivery eye 10 at one end of the angular slit 7 lies within the plane of the vertical longitudinal axis of the shuttle body, and is also disposed at the top of the 55 shuttle head to provide the central top delivery eye herein referred to. Also it will be observed that the receiving eye 9 in the bracket or bracket plate 7 is formed in the vertical leg of such plate so as to be exposed 60 within the end portion of the bobbin recess 3 and receives the filling thread α from the bobbin. It is also to be observed that the slit 7 between the lower eye 9 and the upper eye 10, by reason of its angular 65 characteristic is disposed eccentrically at one

side of the plane of the vertical longitudinal axis of the shuttle body, and therefore acts to deflect the filling thread downwardly and inwardly toward the longitudinal center or axis of the shuttle body whereby said thread 70 will pass through the longitudinal side threading slot 6 of the guide sleeve or tube 5 and thus become engaged within the said sleeve or tube.

The guide sleeve or tube 5 is rigidly fitted 75 to the angular bracket or bracket plate 8 in any suitable manner, such for instance as by a bolt or screw connection 13, though soldering or brazing may be resorted to in the practical manufacture of the device regardless of the manner of securing the guide sleeve or tube 5 to the bracket 8. The said sleeve or tube is arranged inside of the angle of the bracket and is disposed obliquely to the longitudinal axis of the shuttle body, 80 so that the lower or inner end of the sleeve or tube 5 communicates with and is in effect a part of the receiving eye 9, while the outer or upper end of the said sleeve or tube 5 is correspondingly in communication with 85 and is in effect a part of the delivery eye 10 of the device.

It is by reason of the construction described that the shuttle while in flight will become automatically threaded, since the 95 disposition of the angular slit 7 with reference to the slot 6 and the eyes 9 and 10 causes the filling thread to automatically seek a centered position which can only be reached through the slit 7 and the slot 6 100 into the sleeve or tube 5.

In the normal operation of the shuttle, the filling thread which pays out through the guide sleeve 5 is held under proper tension and prevented from slackening back 105 into the bobbin recess by means of a tension device. This tension device preferably consists of a loose friction ball 14 which is loosely housed within the guide sleeve or tube so that the filling thread pulls under 110 and about the said ball with the result of providing a tension on the thread that is quite sufficient without danger of breaking or cutting, as is possible with other forms of friction device. 115

A simplified form of the invention is suggested in Figs. 5, 6 and 7 of the drawings, and consists in the use of a guide sleeve or tube 15 inserted obliquely within the shuttle head 4 and having a top delivery eye 16 and bottom or inner receiving eye 17, these several parts corresponding in position and function to the guide sleeve or tube 5 already described. Also in the modification referred to, the guide sleeve 15 is provided 120 in one side with a longitudinal threading slot 18^a in communication with an eccentrically disposed threading slit 18 cut into the top portion of the shuttle head at one side of the longitudinal vertical center there- 125 130

of, and thus performing the function of the slit 7 previously referred to. Furthermore, the guide sleeve or tube 15 is provided at one of the upper corners of the slit 18 with an 5 inturned guard lip 19 that serves to prevent the filling thread from slipping back through the slot 18 after having been once threaded into the guide sleeve.

Another form of guide sleeve or tube is 10 shown in Figs. 8 and 9 of the drawings and is designated by the reference number 20. This guide sleeve is formed with the lateral or side threading slot 21, and at both edges of said slot the sleeve or tube is formed with 15 inturned guard lips 22 extending the full length thereof and serving to doubly guard the filling thread from slipping back through the slot 21.

Another form of construction is suggested 20 in Figs. 10 and 11 of the drawings, and consists of a guide sleeve or tube 23 having one of its edges, at one side of the threading slot 24 out-turned as at 25 to assist in the threading operation, while, adjacent its delivery 25 eye or upper end, the wall of the sleeve or tube is prick-punched inwardly as at 26 to provide an inside guard projection that holds the filling thread from working back through the threading slot.

30 In all of the forms of guide sleeves described, the same are mounted as illustrated in Figs. 5 and 6 of the drawings, and are intended to carry out the same objects and to perform the same functions as the forms of 35 the invention illustrated in Figs. 1 to 4 inclusive of the drawings.

From the foregoing it will be understood 40 that changes in the form, proportion, and minor details of construction may be resorted to without departing from the spirit or sacrificing any of the advantages of the invention.

What I claim is:

1. A self-threading shuttle provided on 45 the upper side of its head with a horizontal member having therein a top delivery eye, at one end of its bottom recess with a vertical member having a receiving eye whose horizontal axis is at right angles to the vertical 50 axis of the top delivery eye, and at the top with a threading slit connecting the two eyes, and an upstanding inclined guide sleeve lying between and connecting the said two eyes, the said guide sleeve also having a side

threading slot in open communication with 55 the threading slit exposed in the top of the shuttle head.

2. A self-threading shuttle including an angular member provided with a threading slit exposed at the top of the shuttle head 60 and within the bobbin recess, and an up-standing guide sleeve arranged obliquely within the angle of said member and having its delivery eye disposed in the plane of the vertical longitudinal center of the shuttle 65 body and at the top of the shuttle head, said sleeve being provided with a side threading slot in open communication with said slit.

3. A self-threading shuttle including an angular member provided with an angular 70 threading slit exposed at the top of the shuttle head and disposed at one side of the plane of the vertical longitudinal center of the shuttle body, and a guide sleeve arranged obliquely within the angle of said member 75 and having its top delivery eye disposed at the top, and centrally between the sides, of the shuttle body, said sleeve being provided with a side threading slot in open communication with said slit.

4. In a loom shuttle, the combination with a shuttle body, of an angular member provided with an angular slit and having top and bottom terminal eyes, an upstanding guide sleeve for the filling thread arranged 85 within the angle of said member and communicating with said top and side terminal eyes, and a friction ball loosely housed within said sleeve.

5. A self-threading guide for loom shuttles comprising an angular bracket member having a threading slit, and a guide sleeve fitted within the angle of said bracket member and having a side threading slot.

6. A self-threading guide for loom shuttles consisting of an angular bracket plate having an angular threading slit and eyes at the terminals of said slit, and a guide sleeve fitted within the angle of the bracket plate and having its opposite ends communicating 100 respectively with the separate eyes of the bracket plate.

In testimony whereof I hereunto affix my signature in the presence of two witnesses.

FRED A. GUILLETTE.
